UNITED STATES PATENT OFFICE.

MATHEW M. KERR, OF DETROIT, MICHIGAN, ASSIGNOR TO DETROIT DENTAL MANUFACTURING COMPANY, OF DETROIT, MICHIGAN, A CORPORATION OF MICHIGAN.

DENTAL ARTICULATOR.

1,291,919.

Specification of Letters Patent. Patented Jan. 21, 1919.

Application filed June 29, 1918. Serial No. 242,547.

To all whom it may concern:

Be it known that I, MATHEW M. KERR, a citizen of the United States of America, residing at Detroit, in the county of Wayne 5 and State of Michigan, have invented certain new and useful Improvements in Dental Articulators, of which the following is a specification, reference being had therein to the accompanying drawings.

10 This invention relates to dental articulators such as comprise coacting jaws connected to move pivotally to and from each other and to also undergo a slight angular movement in parallel planes.

15 In the use of such a device it is frequently desirable to disconnect the two jaws, but in the constructions hitherto employed the pivotal connection has been such as to require considerable manipulation and loss of time 20 in order to take the jaws apart or put them together.

It is the object of the present invention primarily to provide a dental articulator having a pivotal connection between its 25 jaws, such as will allow the necessary play in parallel planes and will at the same time allow assembly or disassembly of the jaws to be accomplished very quickly and without trouble.

30 A further object is to provide a simplified construction of dental articulator, the jaws of which may be stamped from sheet metal and which will employ a simple and inexpensive means to establish the detachable 35 pivotal connection and to limit the extent to which the jaws may approach each other.

In the accompanying drawings:

Figure 1 is a top view of the invention;

40 Fig. 2 is a view of the same in a side elevation; and

Fig. 3 is a transverse sectional view on line 3—3 of Fig. 2.

In these views the reference characters A and B designate a pair of jaw members, 45 preferably stamped from sheet metal, each of said members comprising an elliptical work-holding portion C, a shank portion D of reduced width, and an intermediate offset E, whereby the space interval between the 50 portions C is made greater than that between the portions D. From the shank of the upper jaw member A, a pair of lugs F project downwardly in spaced relation and terminate in portions projecting toward the 55 members C, in which portions there are

formed slots G. Said slots receive the extremities of a sleeve H, having centrally secured thereto a pair of coiled springs J which extend divergent to respectively engage projections K formed on the lugs F. 60 Thus, said springs tend to maintain the sleeve H adjusted from the free or work-holding ends of the jaws and to resist movement of the sleeve toward said ends. The shank of the lower jaw member B is formed 65 with a pair of opposed upstanding lugs M between which the slotted portions of the lugs F extend and a pin N is removably passed through the lugs M and through the intermediate sleeve H thus establishing pivotal 70 connection between the two jaw members. Preferably said pin N is pointed at one extremity and formed at the other with an eye, the point facilitating introduction of the pin into its bearings formed by the 75 lugs N and the sleeve H, while the eye permits the pin to be readily grasped to withdraw the same from said bearings. Preferably the lugs N are flared from each other slightly at their rear edges, as indicated at 80 M, thus facilitating the introduction of the lugs F between the lugs N when the jaw members are being assembled.

The shank portion of the jaw member A has an adjusting screw O engaged transversely therein, the end of said screw being adapted to engage the shank portion of the member B to limit swinging movement of the jaw members toward each other about the pivot pin. In order to maintain the 85 screw O in any adjusted position with respect to the jaw member C a lock nut P is threaded upon said screw and frictionally engaged with the jaw member A. The rear ends of both jaw members are bent at right 90 angles as indicated at R so that either part 95 R may coact with the portion C of the same jaw member to support the articulator in its normal position, as shown in the drawing.

In Fig. 1 there are shown in dash-line 100 the relative positions which the jaws may assume through a movement in parallel planes and in Fig. 2 there is shown in dash-line a position which the lower jaw may assume in advance of the upper one. 105

When the jaws A and B are assembled, as shown in the drawing, the springs J tend to maintain said jaws in vertical registration, but when a sufficient force is exerted upon the jaws to overcome the resistance of said 110

springs, the jaws may be shifted to either of said dash-line positions. The purpose of extending the slotted portions of the lugs F convergently is to avoid interference between the lugs M and F when the jaws are subjected to relative lateral movement and the convergent form of said lugs F furthermore facilitates introduction of said jaws between the lugs M. When the pin N is removed, the jaws may be readily taken apart, the sleeve H being permanently held in its described relation to the lugs F by the springs J. The primary advantage of the construction lies in the provision of a permanent adjustable bearing carried by one of the jaws to receive the pivot pin, said adjustable bearing being engaged by the springs instead of establishing the latter in direct engagement with the pivot forming member.

What I claim as my invention, is:

1. A dental articulator, comprising a pair of coacting jaw members, pivot bearings respectively carried by said members, one of said bearings being movable relative to the corresponding jaw member transversely of its axis, means yieldably restraining the last-mentioned bearing for movement and a pivot pin detachably engaging said bearings.

2. A dental articulator, comprising a pair of coacting jaw members, a pair of spaced lugs projecting from one of said members in opposed relation and formed with slots extending longitudinally of the jaws, a sleeve having its extremities slidably engaging in said slots, means yieldably restraining the sleeve against movement in said

slots, a pair of lugs projecting from the other jaw member outside of the slotted lugs, and a pivot pin detachably engaging said outer lugs and said sleeve.

3. A dental articulator, comprising a pair of coacting jaw members, a pivot pin carried by one of said jaw members, a pair of spaced lugs projecting from the other jaw member slotted longitudinally thereof, a sleeve loosely receiving said pivot pin and having its extremities slidably engaged in said slots, and means yieldably restraining said sleeve against movement in the slots.

4. A dental articulator comprising a pair of coacting jaw members, a sleeve transversely carried by one of said members, establishing its pivotal axis, said sleeve having a limited movement longitudinally of the member, a means carried by said member yieldably restraining said sleeve against movement, and a pivot pin passing loosely through said sleeve and detachably carried by the other jaw member.

5. A dental articulator, comprising a pair of pivotally connected coacting sheet metal jaws, relatively laterally movable, means yieldably resisting relative lateral movement of said members, and a lug laterally projecting from one of said members and constituting a means for actuating relative lateral movement in opposition to said spring, said lug being twisted into a plane at right angles to that of the member carrying the same and being bent substantially transverse to said member.

In testimony whereof I affix my signature.

MATHEW M. KERR.
